[57] ABSTRACT

A signal synthesizer apparatus having a parameter dependent multiplier which includes charge-coupled devices. The multiplier has a gating input to store a charge corresponding to an input signal applied thereto; a first set of transmission gates for selectively transferring portions of the stored input charge, the selectivity of the transmission gates being dependent on a prescribed parameter; a plurality of intermediate electrodes for storing the charges transferred by the transmission gates; a second set of transmission gates for transferring the charges stored by the intermediate electrodes; and an output electrode for combining all of the charges transferred from the intermediate electrodes by the second set of transmission gates. The signal output by the multiplier corresponds to the magnitude of the combined charges of the output electrode.

SIGNAL SYNTHESIZER APPARATUS

The present invention relates to a signal synthesizer apparatus suitable for synthesizing analog signals such as voice signals.

Active development and practice of apparatus for synthesizing voice signals prevails these days. There are various systems of synthesizing voice signals and they can be generally grouped into either a waveform coding scheme or a parameter scheme. Apparatus of the waveform coding scheme have merit in that the circuit arrangement is simple but a disadvantage in that the degree of compression is not large. On the other hand, apparatus of the parameter scheme have a complicated circuit arrangement, but enable the compression degree to be made extremely large.

FIG. 1 is a block diagram showing a conventional voice synthesizing circuit of a linear predictive coding scheme which is one of the parameter schemes. The one similar to this voice synthesizing circuit is disclosed in a publication "IEEE TRANSACTIONS ON ACOUSTICS, SPEECH, AND SIGNAL PROCESSING," VOL. ASSP-27, No. 6, DECEMBER 1979. In FIG. 1, an electronic switch 11 is intended to switch between a white noise generator 12 and an impulse train generator 13. Impulse signals are used as a signal source to synthesize vocal sounds (vowels and vocal consonants) such as a, u, m and b, and white noises as a signal source to synthesize voiceless consonants such as p, t and f. These white noises and impulse signals may be regarded as a kind of analog signal. White noise and impulse signals are appropriately amplified by an amplifier 14 and then converted by an analog-to-digital converter 15 to a digital signal. The converted digital converter is applied to a time varying digital filter circuit 16 which is the so-called voice filter. The signal passed through the filter circuit 16 is again converted by a digital-to-analog converter 17 to an analog signal, whereby a desired voice signal or a speech output is gained.

FIG. 2A shows an arrangement of filter circuit 16 shown in FIG. 1. The filter circuit 16 is formed of cascade-connected n-stage lattice type filters 16₁-16_n.

FIG. 2B shows a part of filter circuit 16 in which a filter of one stage, 16_{n-1}, comprises digital signal composer circuits 21, 22 having adding and subtracting functions, digital multiplier circuits 23, 24 and a digital signal delay circuit 25. These filters are cascade-connected with one another in eight or twelve stages to form 8- or 12-stage digital filters of full-pole type.

Various voice signals are obtained through this circuit arrangement by changing the signal changeover time of switch 11, that is, the sampling time and parameters K for the filter circuit 16.

Digital multiplier circuits 23 and 24 employed in the filter circuit 16 must process an extremely large amount of data in a short time period, and it is therefore necessary that they achieve high speed operation. In addition, they have an extremely complicated circuit arrangement, so that chip size becomes extremely large upon integration of the circuits, thereby making the cost high. Further, the conventional filter is a digital one, thus making it necessary to include analog-to-digital converter 15 for converting an analog signal applied from the switch 11 to a digital signal, and digital-to-analog converter 17 for converting a digital signal applied from the filter circuit 16 to an analog signal. This is one cause

which makes chip size large upon circuit integration of a voice signal synthesizer.

The present invention is intended to eliminate the above-mentioned drawbacks, and the object of the present invention is to provide a signal synthesizer apparatus in which chips can be easily kept small in size upon circuit integration thereof and no A/D and D/A converters are needed.

For the purpose of achieving the object of the present invention, the signal synthesizer apparatus according to the present invention includes a parameter dependent multiplier in the time varying filter thereof, said multiplier comprising a charge transfer device such as a charge-coupled device (CCD) or a bucket brigade device (BBD). More particularly, the signal synthesizer apparatus includes a parameter dependent multiplier, the parameter dependent multiplier comprising input means for storing an input signal as an input charge, transmission means coupled to the input means for selectively transferring charges of the input charge, the selectivity of transmission means being dependent on a prescribed parameter, an intermediate means for storing charges transferred from the transmission means, and output means coupled to the intermediate means for combining charges stored by the intermediate means so as to provide an output signal.

The signal synthesizer thus arranged needs neither digital multiplier circuits whose arrangement is complicated nor AD/DA converters as the conventional digital type synthesizer does, and can use MOS IC manufacturing techniques already established. Accordingly, the synthesizer according to the present invention enables desired chips to be small-sized upon circuit integration thereof and mass production to be carried out with low cost.

This invention can be more fully understood from the following detailed description when taken in conjunction with the accompanying drawings, in which:

FIG. 1 shows a block configuration of prior art voice signal synthesizer.

FIG. 2A is a block diagram illustrating a construction of time varying digital filter shown in FIG. 1.

FIG. 2B is a block diagram showing in detail the construction of lattice type filter shown in FIG. 2A.

FIG. 3 is a block diagram showing a typical one of voice signal synthesizers according to the present invention.

FIG. 4 is a block diagram showing a construction of lattice type filter unit employed in the synthesizer of FIG. 3.

FIGS. 5A and 5B show a brief construction of analog signal adder shown in FIG. 4.

FIG. 6 shows a brief construction of analog signal attenuator or parameter dependent multiplier shown in FIG. 4.

FIG. 7 shows a brief construction of CCD type analog signal delay circuit shown in FIG. 4.

FIG. 8 is a block diagram showing in detail a construction of lattice type filter shown in FIG. 4.

FIG. 9 is a circuit diagram showing in detail a construction of parameter dependent multiplier shown in FIG. 4 or 8.

FIG. 10 is a circuit diagram showing in detail a construction of another parameter dependent multiplier shown in FIG. 4 or 8.

FIG. 11 is a circuit diagram showing a modification of multiplier shown in FIG. 10.

FIG. 12 is a timing chart illustrating the operation of multiplier shown in FIG. 9.

FIG. 13 shows an equivalent circuit of charge transferring portion of multiplier shown in FIG. 9.

Before proceeding with the description of embodiments of the invention, it will expressly be understood that like reference symbols are used to designate like portions throughout the drawings for simplicity of illustration and that components designated by like reference symbols may easily be replaced with each other or one another with minor change thereof by a person of ordinary skill in the art. An embodiment of a signal synthesizer according to the invention will be described with reference to drawings.

FIG. 3 is a block diagram showing an embodiment of a signal synthesizer circuit according to the invention. This circuit embodiment is different from conventional ones in that the time varying digital filter circuit 16 which is the so-called voice filter is replaced by a time varying analog filter circuit 18 in which a CCD is employed. Therefore, analog-to-digital converter 15 and digital-to-analog converter 17 are made unnecessary and omitted. One stage filter 18_i of filter circuit 18 is formed as shown in FIG. 4, in which numerals 31 and 32 represent analog signal adder circuits which function to add together analog signals, 33 and 34 analog signal attenuator circuits or multipliers, and 35 an analog signal delay circuit. Each of these circuits is formed of a charge transfer device such as CCD (charge coupled device) or a BBD (bucket brigade device). Single stage filters 18_i as described above are cascade-connected in, e.g., eight or twelve stages similar to the conventional manner to form an analog filter of full-pole type.

This circuit arrangement allows high speed operation to be attained similar to prior art ones and makes it unnecessary to use digital multiplier circuits which are complicated in circuit arrangement. Therefore, chips can be easily small-sized upon integration of the circuits. In addition, filter circuit 18 of an analog type is used, so that conventional AD and DA converters are made unnecessary, thus making the arrangement of the filter itself simple and the chips small-sized.

FIGS. 5A and 5B show an example of analog signal adder circuit 31 or 32 including the CCD, in which FIG. 5A is a plane view thereof and FIG. 5B a sectional view thereof. It is assumed that analog signals E1 and E2 having charges Q1 and Q2 are respectively applied to transfer gates 41 and 42 which are controlled by a clock signal ϕ_1 . When a clock signal ϕ_2 is applied under this condition to a transfer gate 43 adjacent to the gates 41 and 42, both of signals E1 and E2 are transferred to the gate 43 and addition of Q1+Q2 is carried out to gain a signal E3.

FIG. 6 is a plane view showing an example of analog signal attenuator or parameter dependent multiplier 33 (or 34) in which the CCD is employed. Since the absolute value of a parameter K is smaller than 1 in the analog attenuator circuit 33 or 34, a case where the parameter K is 0.5 is shown here. It is assumed that an analog signal Ein having a charge Qin is applied to a transfer gate 51 which is controlled by a clock signal ϕ_1 and that a clock signal ϕ_2 is applied under this condition to transfer gates 52 and 53 adjacent to the gate 51. The charge Qin of analog signal Ein is divided by two and a charge of Qin/2 is stored in each of transfer gates 52 and 53, respectively. Thereafter, one of the charges stored in the two transfer gates 52 and 53 is picked out as an output to achieve attenuation of $\frac{1}{2}$. Namely, FIG. 6

shows an analog multiplier whose multiplying number is 0.5.

FIG. 7 is a sectional view showing an example of analog signal delay circuit 35. When a signal charge is applied to a transfer gate 61₁ positioned in the most left-hand side, the signal charge is thereafter transferred to right-hand-side transfer gates 61₂, 61₃, . . . , successively, responsive to clock signals ϕ_1 and ϕ_2 . The signal delay time thus attained is proportional to the number of transfer gates through which the signal charge is transferred, and inversely proportional to the frequency of signals ϕ_1 and ϕ_2 .

According to the invention, the filter circuit is formed of analog signal adder circuits, analog multiplier circuits and an analog signal delay circuit, each of which employs the charge transfer device, thus allowing chips to be small-sized upon the integration of circuits and cost to be lowered.

FIG. 8 shows a detailed arrangement of lattice type filter 18_i shown in FIG. 4. A signal E1 is applied through the terminal D to a first gating input 31₁ of a first adder 31. Applied to a second gating input 31₂ of adder 31 is a signal E2 from a multiplier 34 which will be described later. When a clock pulse ϕ_2 is applied to electrodes 31₃ and 31₄, a charge Q1 corresponding to the potential of signal E1 applied to the input 31₁ is transferred to the electrode 31₃ and a charge Q2 corresponding to the potential of signal E2 applied to the input 31₂ to the electrode 31₄. When a clock pulse ϕ_1 is then applied to an electrode 31₅, charges Q1 and Q2 are transferred to the electrode 31₅. If the charge transfer is attained with an efficiency of 100 percent, a charge Q3 transferred to the electrode 31₅ is equal to Q1+Q2. Even if the efficiency is less than 100 percent, the charge Q3 accurately corresponds to the sum (Q1+Q2) of charges. The charge Q3 is picked out as a signal E3 through an output 31₆. The signal E3 is applied to the terminal C.

The adder 31 or components 31₁ to 31₆ have the CCD structure of conventional 2-phase type. Clock pulses ϕ_1 and ϕ_2 can also be obtained from a conventional 2-phase clock pulse generator 36.

The signal E3 is converted by a multiplier 33 to a signal E4. The multiplier 33 multiplies the signal E3 by a given parameter $-K(|K| \leq 1)$ to produce E4=-KE3.

The signal E4 is applied to a first gating input 32₁ of a second adder 32. Applied to a second gating input 32₂ is a signal E5. The signal E5 corresponds to a signal E7 applied to the terminal A, that is, to a signal picked out after the signal E7 is delayed by a given time period. The delay of signal E7 is carried out using a conventional CCD delay circuit 35. The CCD of 2-phase type is employed here, but another phase type or analog delay line of other type may be used. A charge Q4 corresponding to the potential of signal E4 and a charge Q5 corresponding to the potential of signal E5 are transferred to electrodes 32₃ and 32₄ responsive to the clock pulse ϕ_2 . Charges Q4 and Q5 are then transferred to an electrode 32₅ responsive to the occurrence of clock pulse ϕ_1 . A charge Q6 transferred to the electrode 32₅ corresponds to Q4+Q5. The charge Q6 is picked out as a signal E6 from the terminal B through an output 32₆.

The signal E5 is converted through the already-described multiplier 34 to the signal E2. The multiplier 34 multiplies the signal E5 by a given parameter $K(|K'|=1)$ to produce E2=KE5.

FIG. 9 shows in detail the parameter dependent multiplier 34 shown in FIG. 8. An input signal E_{in} (or the signal E_5) is applied to a gating input 90. A charge Q_{in} corresponding to the potential of signal E_{in} is stored in an input electrode 92. The electrode 92 is coupled via transmission gates 94₁, 94₂, 94₃ and 94₄ to electrodes 96₁, 96₂, 96₃ and 96₄ respectively. Electrodes 96₁ to 96₄ are connected via transmission gates 98₁ to 98₄ to an output electrode 100. A charge ΣQ_i ($i=a, b, c, d$) is picked out as an output signal E_{out} (or the signal E_2) through an output 102.

Gate inputs G1 to G4 of transmission gates 94₁ to 94₄ are obtained from outputs of AND gates 104₁ to 104₄. The clock pulse ϕ_1 is applied to first inputs of gates 104₁ to 104₄, whose second inputs are connected to a 4-bit register 106. Gates 104₁ to 104₄ transmit contents R1 to R4 of register 106 to transmission gates 94₁ to 94₄ when the pulse ϕ_1 becomes logic "1". When R1, R2, R3, R4=0101 and the pulse ϕ_1 is at logic "1", for example, gates 104₂ and 104₄ are made open. Accordingly, outputs G1, G2, G3, G4 of gates 104₁ to 104₄ become equal to 0101 to make only gates 94₂ and 94₄ open. A portion of charge Q_{in} is transferred to electrodes 96₂ and 96₄ in this case. The charge Q_{in} is divided at a given rate when transferred to electrodes 96₁ to 96₄, and it will be described later with reference to FIG. 13.

Contents of register 106 are determined by a sequencer 108, which may have the same arrangement as that of model Am2909 made by Advanced Micro Devices Inc., USA, for example. The sequencer 108 supplies address designation data CS to an external ROM 110. Stored in the ROM 110 are data representing given K parameters. For example, if data CS designates the 100th address, data K_{100} stored in the 100th address of ROM 110 is read through the sequencer 108. When the data K_{100} is loaded in the register 106, either of transmission gates 94₁ to 94₄ corresponding to the data K_{100} is made through upon the occurrence of pulse ϕ_1 . When the pulse ϕ_2 is then incremented by one, a sequence counter in the sequencer 108 is incremented by "1", thus causing data CS to designate the 101th address. K parameter in the 101th address is loaded at this time in the register 106. The sequencer 108 thus determines the conduction state of a gating matrix or a K parameter matrix formed by transmission gates 94₁ to 94₄. The k parameter changes every moment responsive to the clock pulse ϕ_2 applied to the sequencer 108.

FIG. 12 shows a sequence of above-described operation. The K parameter is determined by contents K_{n-1} in the (n-1)th address of ROM 110 before a time t_{10} (FIG. 12D). When the pulse ϕ_2 becomes logic "1" at the time t_{10} (FIG. 12A), data CS designates n-th address and the K parameter becomes contents K_n in the n-th address (FIG. 12D). When the pulse ϕ_1 becomes logic "1" at a time t_{12} (FIG. 12B), transmission gates 94₁ to 94₄ corresponding to contents K_n are made through. When the pulse ϕ_2 becomes logic "1" at a time t_{14} (FIG. 12A), all of transmission gates 98₁ to 98₄ are made through, causing charges Q_a to Q_d of electrodes 96₁ to 96₄ to be transferred to the electrode 100. After the time t_{14} , the same operation is carried out as that achieved after the time t_{10} . Namely, transmission gates 94₁ to 94₄ corresponding to contents K_{n+1} are made through at a time t_{16} and transmission gates 98₁ to 98₄ are made through at a time t_{18} .

The multiplier K, i.e. $K=E_{out}/E_{in}=\Sigma Q_i/Q_{in}$, of multiplier 34 shown in FIG. 9 varies depending upon contents R1 to R4 of register 106. It is assumed that the

capacitance of electrode 92 is C_{in} , that capacitances of electrodes 96₁, 96₂, 96₃ and 96₄ are C_a , C_b , C_c and C_d , respectively, and that electrodes 92 and 96₁ to 96₄ are arranged to establish $C_{in}=2C_a=4C_b=8C_c=16C_d$ (ratios of C_a to C_d relative to C_{in} and the number of electrodes 96 can be determined optionally).

FIG. 13 is now referred to under the assumption considering a case where contents R1 to R4 of register 106 is 1001. Only transistors 94₁ and 94₄ of MOS transistors forming transmission gates 94₁ to 94₄ are rendered conductive at first. In this case, a charge Q_a corresponding to $Q_{in}/2$ is transferred to the electrode 96₁ and a charge Q_d corresponding to $Q_{in}/16$ is transferred to the electrode 96₄. And when all of MOS transistors forming transmission gates 98₁ to 98₄ are then made conductive, a charge ΣQ_i having such magnitude as corresponds to $Q_{in}/2+Q_{in}/16=(9/16) Q_{in}$ is transferred to the electrode 100. As apparent from the above description, the magnitude of ΣQ_{in} varies depending upon contents of register 106. In another words, the multiplier K of multiplier 34 varies responsive to the repeat of clock pulse ϕ_2 according to data stored in the ROM 110.

FIG. 10 shows in detail the parameter dependent multiplier 33 shown in FIG. 8. The multiplier shown in FIG. 10 has the same arrangement as that of multiplier shown in FIG. 9. $+K$ ($K \leq 1$) is used as the multiplier in FIG. 9 and $-K$ in FIG. 10. An inverter array or complementary circuit 109 of 4-bit is arranged between the sequencer 108 and a register 106a to produce $-K$. Namely, a complementary relation is established between the contents of register 106 shown in FIG. 9 and those of register 106a shown in FIG. 10.

FIG. 11 shows a modification of multiplier shown in FIG. 10. No complementary circuit is used in the multiplier shown in FIG. 11, but data corresponding to $-K$ is stored instead in a ROM 110a itself.

Although specific constructions have been illustrated and described herein, it is not intended that the invention be limited to the element and construction disclosed. One skilled in the art will recognize that other particular elements or subconstruction may be used without departing from the scope and spirit of the invention. The present invention can be applied to voice synthesizing apparatus of another type such as that of a linear predictive coding scheme. Further, the parameter dependent multiplier (attenuator) as shown in FIG. 9 can be applied to analog equipments as well as voice synthesizers.

When the construction of FIG. 9 further includes an inverter connected in series with the signal path, such construction may be used for the $-K$ parameter dependent multiplier 33.

What is claimed is:

1. A signal synthesizer apparatus including a parameter dependent multiplier which comprises:
input means for receiving an input signal and storing an input charge corresponding to said input signal; transmission means coupled to said input means for selectively transferring discrete charges corresponding to predetermined portions of said input charge, the selectivity of said transmission means being dependent on a prescribed parameter; intermediate means for storing said discrete charges transferred by said transmission means; and output means coupled to said intermediate means for combining said discrete charges stored by said

intermediate means and providing an output signal corresponding to the combined charges.

2. A signal synthesizer apparatus comprising:

delay means receiving a signal A for delaying said signal A by a given time and providing a delayed signal corresponding to said signal A;

first adder means coupled to said delay means for adding said delayed signal to a first multiplied signal and providing a signal B;

first multiplier means coupled to said delay means for multiplying said delayed signal by a first prescribed parameter and providing a second multiplied signal;

second adder means receiving a signal D for adding the signal D to said second multiplied signal and providing a signal C; and

second multiplier means coupled to said first and second adder means for multiplying said signal C by a second prescribed parameter and providing said first multiplied signal,

wherein said first multiplier means includes:

input means for storing an input charge corresponding to said delayed signal applied thereto;

transmission means coupled to said input means for selectively transferring discrete charges corresponding to predetermined portions of said input charge, the selectivity of said transmission means being dependent on said first prescribed parameter;

intermediate means for storing said discrete charges transferred by said transmission means; and

output means coupled to said intermediate means for combining said discrete charges stored by said intermediate means and providing said second multiplied signal.

3. A signal synthesizer apparatus comprising: delay means receiving a signal A for delaying said signal A by a given time and providing a delayed signal corresponding to said signal A;

first adder means coupled to said delay means for adding said delayed signal to a first multiplied signal and providing a signal B;

first multiplier means coupled to said delay means for multiplying said delayed signal by a first prescribed parameter and providing a second multiplied signal;

second adder means receiving a signal D for adding the signal D to said second multiplied signal and providing a signal C; and

second multiplier means coupled to said first and second adder means for multiplying said signal C by a second prescribed parameter and providing said first multiplied signal,

wherein said second multiplier means includes:

input means for storing an input charge corresponding to said signal C applied thereto;

transmission means coupled to said input means for selectively transferring discrete charges corresponding to predetermined portions of said input charge, the selectivity of said transmission means being dependent on said second prescribed parameter;

intermediate means for storing said discrete charges transferred by said transmission means; and output means coupled to said intermediate means for combining said discrete charges stored by said intermediate means and providing said first multiplied signal.

4. A signal synthesizer apparatus comprising:

delay means receiving a signal A for delaying said signal A by a given time and providing a delayed signal corresponding to said signal A;

first adder means coupled to said delay means for adding said delayed signal to a first multiplied signal and providing a signal B;

first multiplier means coupled to said delay means for multiplying said delayed signal by a first prescribed parameter and providing a second multiplied signal;

second adder means receiving a signal D for adding the signal D to said second multiplied signal and providing a signal C; and

second multiplier means coupled to said first and second adder means for multiplying said signal C by a second prescribed parameter and providing said first multiplied signal,

wherein said first multiplier means includes:

input means for storing an input charge corresponding to said delayed signal applied thereto;

transmission means coupled to said input means for selectively transferring discrete charges corresponding to predetermined portions of said input charge, the selectivity of said transmission means being dependent on said first prescribed parameter;

intermediate means for storing said discrete charges transferred by said transmission means; and

outputs means coupled to said intermediate means for combining said discrete charges stored by said intermediate means and providing said second multiplied signal,

wherein said second multiplier means includes:

input means for storing an input charge corresponding to said signal C applied thereto;

transmission means coupled to said input means for selectively transferring discrete charges corresponding to predetermined portions of said input charge, the selectivity of said transmission means being dependent on said second prescribed parameter;

intermediate means for storing said discrete charges transferred by said transmission means; and

output means coupled to said intermediate means for combining said discrete charges stored by said intermediate means and providing said first multiplied signal.

5. An apparatus of claim 1, wherein said transmission means comprises:

a plurality of transmission gates, each being connected between a first transfer electrode of said input means and one of a plurality of second transfer electrodes of said intermediate means, each of said second transfer electrodes being coupled through each of said transmission gates to said first transfer electrode; and

gating means coupled to said transmission gates for determining the conduction state of each of said transmission gates in accordance with a gating data corresponding to said prescribed parameter.

6. An apparatus of claim 2 or 4, wherein said transmission means comprises:

a plurality of transmission gates, each being connected between a first transfer electrode of said input means and one of a plurality of second transfer electrodes of said intermediate means, each of said second transfer electrodes being coupled through each of said transmission gates to said first transfer electrode; and

gating means coupled to said transmission gates for determining the conduction state of each of said transmission gates in accordance with a gating data corresponding to said first prescribed parameter.

7. An apparatus of claim 3 or 4, wherein said transmission means comprises:

a plurality of transmission gates, each being connect between a first transfer electrode of said input means and one of a plurality of second transfer electrodes of said intermediate means, each of said second transfer electrodes being coupled through each of said transmission gates to said first transfer electrode; and

gating means coupled to said transmission gates for determining the conduction state of each of said transmission gates in accordance with a gating data corresponding to said second prescribed parameter.

8. An apparatus of claim 5, wherein said transmission means further comprises:

memory means for storing a predetermined data representing said prescribed parameter;

control means coupled to said memory means for sequentially reading out said predetermined data; and

register means coupled to said control means for storing said predetermined data read out and providing said gating data to said transmission gates.

9. An apparatus of claim 6, wherein said transmission means further comprises:

memory means for storing a predetermined data representing said first prescribed parameter;

control means coupled to said memory means for sequentially reading out said predetermined data; and

register means coupled to said control means for storing said predetermined data read out and providing said gating data to said transmission gates.

10. An apparatus of claim 7, wherein said transmission means further comprises:

memory means for storing a predetermined data representing said second prescribed parameter;

control means coupled to said memory means for sequentially reading out said predetermined data; and

register means coupled to said control means for storing said predetermined data read out and providing said gating data to said transmission gates.

11. An apparatus of claim 8, wherein said transmission means further comprises complementary means connected between said control means and said register means for converting said predetermined data read out to a complementary data, said complementary data being stored in said register means and said gating data corresponding to said complementary data.

12. An apparatus of claim 9, wherein said transmission means further comprises complementary means connected between said control means and said register means for converting said predetermined data read out to a complementary data, said complementary data being stored in said register means and said gating data corresponding to said complementary data.

13. An apparatus of claim 10, wherein said transmission means further comprises complementary means connected between said control means and said register means for converting said predetermined data read out to a complementary data, said complementary data being stored in said register means and said gating data corresponding to said complementary data.

14. An apparatus of claim 5, 8 or 11, wherein said output means includes a third transfer electrode, and a plurality of second transmission gates connected between each of said second transfer electrodes and said third transfer electrode.

15. An apparatus of claim 14, wherein said parameter dependent multiplier further includes generator means for providing a first pulse and a second pulse, said first pulse being applied to said gating means and said second pulse being applied to said second transmission gates so that said transmission gates are conductive according to said gating data at the time when said first pulse is applied and said second transmission gates are conductive at the time when said second pulse is applied.

16. An apparatus of any of claims 5 to 14 and 15, wherein a capacitance associated with each of said second transfer electrodes is less than a capacitance associated with said first transfer electrode so that said discrete charges transferred from said first transfer electrode to each of said second transfer electrodes are charge-divided.
